SAMUEL SEGAL, OF NEW YORK, N. Y.

COMPOUND DEAD-BOLT MECHANISM.

1,332,958.

Specification of Letters Patent.

Patented Mar. 9, 1920.

Application filed January 15, 1918, Serial No. 211,947. Renewed January 13, 1920. Serial No. 351,252.

To all whom it may concern:

Be it known that I, SAMUEL SEGAL, a citizen of the United States, residing at New York, in the county of New York and State of New York, have invented certain new and useful Improvements in Compound Dead-Bolt Mechanism; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in lock mechanisms; and the invention has reference, more particularly, to a novel construction of compound dead bolt and actuating mechanism therefor.

The invention has for its principal object to provide a simple, strong and efficient dead bolt device having a compound movement and relation to the striking member of the lock mechanism, whereby the same is capable of moving longitudinally into the receiving socket of the striking member, and at the same time is equipped with auxiliary bolt elements which move transversely of the main bolt to engage the walls of the striking member within the receiving socket thereof, to the end that said striking member is engaged in a manner adapted to prevent the same from being pried away from the main bolt during any effort to forcibly violate the lock mechanism.

Another object of the present invention is to provide a novel construction of actuating mechanism, subject to the control of both knob or finger piece and key-mechanism, whereby the novel compound bolt, comprising the main bolt and its auxiliary bolt elements, is readily moved into or out of operative relation to the striking member of the lock mechanism.

Other objects of the present invention, not at this time more particularly enumerated, will be clearly understood from the following detailed description of the same.

With the various objects of my present invention in view, the same comprises, primarily, the novel construction of compound dead bolt mechanism hereinafter set forth; and, the invention consists, furthermore, in the novel arrangements and combinations of

the various devices and parts, as well as in the details of the construction of the same, all of which will be hereinafter more fully described, and then finally embodied in the 60 claims appended to this specification.

The invention is clearly illustrated in the accompanying drawings, in which:—

Figure 1 is a plan view of the novel construction of compound dead bolt mechanism 65 viewed from the rear-side of the same, the casing and striking member, together with a portion of the main bolt being shown in vertical section, and the bolt mechanism being shown in unlocked or withdrawn relation to 70 the striking member; Fig. 2 is a similar view, but showing the bolt mechanism in locked or projected relation to the striking member; Fig. 3 is a horizontal cross section, taken on line 3—3 in said Fig. 1, looking 75 downward; and Fig. 4 is a detail end view of the compound dead bolt with its auxiliary bolt elements, as related to a cam slot plate, the latter being shown in section.

Similar characters of reference are employed in all of the hereinabove described views, to indicate corresponding parts.

Referring now to the said drawings, the reference character 1 indicates a casing for inclosing the lock mechanism the same having in one end wall a suitably disposed opening 2 through which the dead bolt device is projected, and the reference character 3 indicates a striking member provided with an opening 4 through which the dead bolt device may project into the receiving socket 5 thereof.

The reference character 6 indicates the main bolt of the dead bolt device, the same being provided at its inner end with tail-frame 7 integrally connected therewith. Said tail-frame 7 is provided in its body with a longitudinally extending slot 8 providing a guide means which slidably engages a guide-post 9 extending inwardly 100 from the front wall of said casing 1, whereby the bolt mechanism is guided and maintained against undue lateral movement or displacement during its longitudinal movement. Said tail-frame 7 is also cut away 105 adjacent to its free inner end to provide the same with an opening 10, which preferably extends from the end of the said slot 8. Said casing 1 is further provided with laterally disposed webs 11, which terminate at 110 each side marginal edge of said tail-frame 7, and which serve as additional guiding

means to prevent lateral displacement of the bolt device during its longitudinal movement. Projecting laterally from that side of the tail-frame 7 which faces inwardly, or toward the front wall of the casing 1, are a pair of projections or abutments 12 and 13, and, in like manner projecting laterally from the outwardly facing or opposite side of the tail-frame 7, are a pair 5 of similarly located projections or abutments 14 and 15. The said pairs of projections or abutments are positioned to receive the actuating engagement of rotary tumblers for imparting operative movement 10 to the tail-frame 7 and the bolt 6, as will presently be more particularly described. Pivotaly mounted upon a journal-stud 16 connected with said tail-frame 7 is a detent-member 17, which extends rearwardly from 15 its pivoted end beneath the guide-post 9, its free end 18 extending beneath and terminating between said projections or abutments 14 and 15, said free end having an inwardly and laterally extending tongue 19, 20 which extends through said opening 10 and normally lies between the respective projections or abutments 12 and 13, and 14 and 15. Connected with the upper marginal edge of said detent-member is a stop-lug 20, 25 which normally engages the rear side of said post 9, thereby locking said bolt device against forward longitudinal movement until said detent-member is depressed to free 30 said stop-lug from such engagement with said post 9. Connected with said detent-member 17 is a spring-member 22, the free end of which is anchored upon an anchor-stud 23 connected with said tail-frame 7, said spring-member serving to maintain and 35 return said detent-member 17 to normal position with its stop-lug 20 in engagement with said post 9.

The front wall of said casing 1 is provided with a suitably located bearing-portion 24 in which is rotatably mounted the shank 25 of a knob or finger-piece 26. The inner end of said shank is provided with a squared portion 27 upon which is fixed a tumbler 28 having oppositely extending 40 tumbler arms 29. Connected with said tumbler 28 is a boss 30 having an angularly shaped periphery. Secured in connection with anchor-studs 31, connected with the front wall of said casing 1, is a leaf-spring 50 32, the free end of which is shaped to yieldingly engage the angular periphery of said boss 30, to normally hold the tumbler 28 in an initial position. The said tumbler 28 is so positioned that, when the same is rotated by the knob or finger-piece 26, one of its arms 29 is carried into engagement with the projection or abutment 12 of said tail-frame 7. Before operatively engaging said projection or abutment 12, however, the rotated tumbler arm 29 strikes said tongue 19

at the free end 18 of the detent-member 17, thereby effecting a downward swinging movement of the latter against the tension of its spring-member 22. This downward swinging movement of said detent-member 70 17 lowers said stop-lug 20 away from its engagement with the post 9, thus freeing the bolt device for forward longitudinal movement after which the tumbler-arm 29 passes into pushing engagement with said projection or abutment 12, thereby causing the tail-frame 7 and the bolt devices connected therewith, to move longitudinally forward, to project the bolt devices into locking engagement with the striking member 3. As 80 the tumbler 28 completes a half revolution, the tumbler arm 29 is returned to a normal horizontal position, and thereupon moves away from the projection or abutment 12, at the same time freeing said tongue 19 to 85 permit the spring-member 22 to return said detent-member 17 to normal position, except that, owing to the forward longitudinal movement which has in the meantime been imparted to the tail-frame and bolt device, 90 the stop-lug 20 now engages the opposite or outer side of said post 9, so that the detent-member 17 now serves to hold the tail-frame 7 and the bolt device against rearward longitudinal movement, or, in other words, 95 from being pushed back, by other than proper manipulation, into the casing 1.

The tail-frame 7 and the bolt device being in forwardly moved or locking position, the same may be retracted by turning the knob or finger-piece 26 in the opposite direction. Such movement rotates the tumbler arm 29 in the reverse direction, and carries the same past the projection or abutment 12, first into engagement with the tongue 19 to again depress the detent-member 17 to free its stop-lug 20 from engagement with the post 9, and then into rearwardly pushing engagement with the opposite projection or abutment 13, thereby causing the tail-frame 7, 110 and the bolt device connected therewith, to move longitudinally rearward, to retract the bolt device from the striking member 3. The completion of the tumbler's movement permits the detent-member 17 to again move 115 into holding engagement with the post 9.

The lock mechanism is covered over by an inlay or cover-plate 33, which is engaged against stops 34 integrally connected with the walls of the casing 1, and which is secured in place by means of a fastening screw 35 which screws into the free end of said post 9. Mounted to rotate in a bearing opening 36 provided in said cover-plate 33 is rotatable member 37 provided on its inner end with a tumbler 38 adapted to coöperate with the projections or abutments 14 and 15 and the detent-member 17 in the same manner as does the tumbler 28 with the projections or abutments 12 and 13 and 130

the detent-member 17, to cause the locking and retracting movements of the tail-frame 7 and bolt device connected therewith. Said tumbler 38 is actuated by means of a 5 suitable key controlled mechanism, such as a pin-tumbler lock 39 secured in the usual manner within the body of the door 40 upon which the bolt-mechanism is mounted. The coupling-bar 41 of said pin-tumbler lock 10 39 is engaged with said rotatable member 37 so that rotary movement applied to said coupling-bar by the operation of said pin-lock with a proper key, will in turn be transmitted through said rotatable member 15 37 to said tumbler 38.

The main bolt 6 of the device is provided with a pair of oppositely extending transversely oblique guideways or openings 42 which cross one another. Arranged slidably 20 within said guideways or openings 42 are auxiliary bolt elements 43, so disposed by said guideways or openings as to be capable of being respectively projected outwardly from the upper and lower sides of 25 said main bolt 6 at points adjacent to the free end of the latter. Each auxiliary bolt element is provided with a tail-piece 44 of reduced thickness so that the same will pass each other slidably at the juncture of said 30 guideways or openings 42 where the latter cross each other. Said tail-pieces 44 project outwardly from the rearward ends of said guideways or openings 42 respectively beyond the upper and lower sides of said 35 main bolt 6. Affixed to the outer free end of each tail-piece 44 is an inwardly extending pin or lug 45. Fixed within said casing 1 between the inner face of said main bolt 6 and the front wall of said casing 1 is a 40 cam-slot plate 46, the same being preferably mounted upon bosses 47 connected with the front wall of said casing 1 to space the said cam-slot plate slightly away from the surface of said front wall, and said cam-slot 45 plate being immovably secured by means of rivet portions 48 extending through the plate from said bosses 47. Formed in said cam-slot plate are a pair of cam-slots 49, the same being disposed parallel to the longitudinal 50 direction of movement of said main bolt 6 for the greater portion of their extent, but being provided at their outer ends with oblique cam-portions 50 inclined toward the main bolt 6. Each pin or lug 55 45 is engaged in the respective cam-slot adjacent to the free end of the tail-piece 44 to which the said pin or lug is secured.

The operation of the auxiliary bolt elements is as follows:—

60 As the tail-frame 7 and the main bolt 6 is moved longitudinally outward, in the manner above described, the pins or lugs 45 ride forwardly in the parallel portions of said cam-slots and consequently without im- 65 parting any outward movement to said

auxiliary bolt elements while said main bolt 6 is initially entering through the opening 4 into the receiving socket 5 of said striking member 3. Before the outward movement of said main bolt 6 is quite completed, however, the pins or lugs 45 enter said cam-portions 50 of said cam-slots, and in riding therein, impart to each tail-piece 44 an inward thrust, which causes the auxiliary bolt elements 43 to be projected 70 outwardly from the main bolt 6 into the receiving socket 5, the completion of the outward projection of said auxiliary bolt elements coinciding with the completion of the outward longitudinal movement of said 75 main bolt 6. The result of this operation is illustrated in Fig. 2 more particularly, and as there appears, this outward projection of the auxiliary bolt elements extends the same beyond the marginal edges of the opening 4 of the striking member 3. Preferably the walls of said striking member are thickened above and below said opening 4, as at 51, so that the sides of the projected auxiliary bolt elements may engage said 80 thickened parts if desired. When thus projected the auxiliary bolt elements offer obstruction to any attempt to pry away the striking member 3 from the projected main bolt 6, as will be clearly apparent. In 85 the retracting movement of the main bolt 6, the cam-portions 50 acting on the pins or lugs 45 serve to withdraw or retract the auxiliary bolt elements into said main bolt 6, so that the withdrawing or retracting 90 movement of said main bolt through said opening 4 of the striking member 3 may be continued until completely accomplished, as will also be understood.

In its broader aspects my invention resides primarily in the novel construction of compound dead bolt, comprised in the main bolt 6 and the auxiliary bolt elements associated therewith, without regard to the particular mechanism by means of which 100 the longitudinal projecting and retracting movements are imparted to said main bolt 6.

I am aware that some changes may be made in the several arrangements and combinations of the various devices and parts, 105 as well as in the details of the construction of the same, without departing from the scope of my present invention as above described, and as defined in the appended claims. Hence, I do not limit my invention 110 to the exact arrangements and combinations of parts set forth in the above specification, nor do I confine myself to the exact details of the construction of said parts as illustrated in the accompanying drawings. 115

I claim:—

1. In a lock mechanism the combination with a dead bolt and means for actuating the same of auxiliary bolt elements, said dead bolt having oblique oppositely extend- 120

- 4
- ing guideways therethrough for said auxiliary bolt elements respectively terminating at their forward ends in the sides of said dead bolt adjacent to its outer free end, tail-pieces connected with each auxiliary bolt element extending rearwardly through said guideways so as to project exteriorly from the sides of said dead bolt adjacent to its inner end, and means associated with said lock mechanism in operative engagement with said tail pieces for projecting said auxiliary bolt elements upon longitudinal movement of said dead bolt.
2. In a lock mechanism the combination with a dead bolt and means for actuating the same of auxiliary bolt elements, said dead bolt having oblique oppositely extending guideways therethrough for said auxiliary bolt elements respectively terminating at their forward ends in the sides of said dead bolt adjacent to its outer free end, tail-pieces connected with each auxiliary bolt element extending rearwardly through said guideways so as to project exteriorly from the sides of said dead bolt adjacent to its inner end, a fixed cam-slot plate associated with said lock-mechanism having cam-slots therein, and pins fixed to the free ends of said tail-pieces respectively engaged in said cam-slots whereby longitudinal movement of said dead bolt carries said pins in operative engagement with the cam-portions of said cam-slots to project said auxiliary bolt elements after said dead bolt enters a striking member.
3. A compound dead bolt comprising a longitudinally movable main bolt, means for actuating said main bolt, an obliquely and transversely disposed auxiliary bolt slidably associated with said main bolt and adapted to be projected from the side of said main bolt when the latter enters a striking member, and means engaging the rearward end of said auxiliary bolt for imparting a longitudinal projecting movement thereto prior to the completion of the projecting movement of said main bolt.
4. A compound dead bolt comprising a longitudinally movable main bolt, means for actuating said main bolt, an obliquely and transversely disposed auxiliary bolt slidably associated with said main bolt and adapted to be projected from the side of said main bolt when the latter enters a striking member, and means engaging the rearward end of said auxiliary bolt for imparting a longitudinal projecting movement thereto prior to the completion of the projecting movement of said main bolt, comprising a fixed cam-slot plate having a cam-slot formed therein, and a pin projecting from the rear end of said auxiliary bolt into said cam-slot.
5. A compound dead bolt comprising a longitudinally movable main bolt, means for actuating said main bolt, said main bolt hav-
- ing a pair of crossed oblique guideways extending transversely and oppositely through its body the respective outer ends of which terminate on opposite sides of said main bolt adjacent to its outer free end while the respective inner ends of which terminate on opposite sides of said main bolt adjacent to its inner end, a pair of auxiliary bolt elements slidably disposed respectively in said guideways and adapted to be projected from said outer ends of the latter, tail-pieces connected with each auxiliary bolt element projecting rearwardly from the inner ends of said guideways, a fixed cam-slot plate back of said main bolt having cam-slots therein, and pins projecting from the free ends of said tail-pieces into said cam-slots whereby longitudinal movement of said main bolt causes said pins to ride in contact with the cam-portions of said cam-slots to transmit a projecting movement to said auxiliary bolt elements after said main bolt enters a striking member.
6. In a lock-mechanism a casing, a dead-bolt longitudinally movable in said casing for projection from the end thereof, a striking member having an opening in its front wall to receive said dead bolt, a tail-frame connected with said dead-bolt, a fixed post within said casing upon which said tail-frame is guided during its longitudinal movement, a spring pressed detent-member on said tail-frame adapted to engage said post to hold said tail-frame at the limit of either its projected or retracted movement, abutments on said tail-frame, rotary tumbler means for engaging said abutments to impart movement to said tail-frame, means connected with said detent-member engageable by said tumbler means to release said detent-member from said post prior to the operative engagement of said tumbler means with said abutments, said dead bolt having a pair of crossed oblique guideways extending transversely and oppositely through its body the respective outer ends of which terminate on opposite sides of said dead bolt adjacent to its outer free end while the respective inner ends of which terminate on opposite sides of said dead bolt adjacent to its inner end, a pair of auxiliary bolt elements slidably disposed in said guideways and adapted to be projected from the outer ends of the latter, tail-pieces connected with each auxiliary bolt element projecting rearwardly from the inner rear ends of said guideways, a fixed cam-slot plate beneath said dead bolt having cam-slots therein, and pins projecting from the free ends of said tail-pieces into said cam-slots whereby longitudinal movement of said dead bolt causes said pins to ride in contact with the cam-portions of said cam-slots to transmit a projecting movement to said auxiliary bolt elements after said dead bolt enters through the opening of

said striking member so that said auxiliary bolts are projected beyond the marginal edges of said opening of said striking member and within the interior of the latter.

- 5 7. A compound dead bolt comprising a main bolt and crossed oppositely and obliquely projectable auxiliary bolt elements slidably related thereto, and cam means for each auxiliary bolt element coöperating with 10 the rearward ends thereof to project and retract the same respectively upon projecting and retracting longitudinal movement of said main bolt.

- 15 8. A compound dead bolt comprising a main bolt and oppositely and transversely oblique auxiliary bolt elements slidably re-

lated thereto, a cam-plate having cam-slots therein, the inner ends of said cam-slots being parallel to the direction of movement of said main bolt while the outer ends of said cam-slots are parallel to the oblique direction of movement of said auxiliary bolt elements, and pins connected with the rearward ends of said auxiliary bolt elements adapted to ride respectively in said cam-slots. 20 25

In testimony that I claim the invention set forth above I have hereunto set my hand this 9th day of January, 1918.

SAMUEL SEGAL.
